[57] ABSTRACT

A time-controlled cigarette dispenser so to limit the frequency of availability thereof to a smoker, in order to decrease the amount of harm by nicotine to a person's body; the device consisting of a container from which one cigarette is dispensed at a time by a mechanism that is powered by a time-regulated motor.

SHEET 2 OF 2

CIGARETTE CONTROL DISPENSER

This invention relates generally to article dispensers. More specifically it relates to dispensers of cigarettes.

It is generally now well-known to most persons, that the smoking of cigarettes has been concluded as hazardous to good health, and cigarette manufacturers are obliged accordingly to print such warning on all their cigarette packages as well as in all their advertising. Never-the-less in spite thereof, the smoking habit is so strong, that smokers find it hard to resist. Various methods have been accordingly popularized whereby smokers will smoke less, such as by placing cigarettes in readily inaccessible places, as for example, in a chandelier so a person is obliged to climb up on a chair to reach the same. Therefore a need exists at this time for a more practical way of controlling the availability of cigarettes to a smoker.

Accordingly it is a principle object of the present invention to provide a cigarette dispenser that automatically limits the frequency of a cigarette availability.

Another object is to provide a cigarette dispenser in which only one cigarette at a time becomes accessible.

Other objects are to provide a time controlled cigarette dispenser which is simple in design, inexpensive to manufacture, rugged in construction, easy to use and efficient in operation.

These and other objects will be readily evident upon a study of the following specification and the accompany drawing wherein:

FIG. 1 is a perspective view of one design of the present invention, and which is electrically powered.

FIG. 2 is a similar view of a slightly modified model thereof.

FIG. 3 is a cross sectional view taken on line 3—3 of FIG. 2 and which is shown to be powered by a key wound mechanical timer.

FIG. 4 is an exploded perspective view of the dispensing mechanism thereof.

FIG. 5 is a perspective view of another design of the present invention.

FIG. 6 is a cross sectional view taken on line 6—6 of FIG. 5.

FIG. 7 is a cross sectional view taken on line 7—7 of FIG. 6, and which is shown to be powered by a dry cell battery.

FIG. 8 is a detail showing a key operated timer.

Reference is now made to the drawings in detail, and more particularly to FIGS. 1 through 4 at this time, wherein the reference numeral 10 represents a cigarette control dispenser according to the present invention. The dispenser includes a hopper 11 integrally mounted upon a case 12 that contains a dispensing mechanism 13 and a motor or timer 14 that can be electrically powered (as shown by the model illustrated in FIG. 1) or mechanically powered (as shown by the model illustrated in FIGS. 2 and 3).

The hopper 11 comprises an enclosure made of transparent hard plastic so to allow observation thereunto, and which has one or more openings 15 high on one end thereof so that cigarettes 16 may be loaded thereinto.

The case may be of any shape that is pleasing in appearance such as a sphere 17 integral with or placable upon a cylindrical base 18, as suggested in the drawing.

The timer 14 may be an electric motor in an electric circuit with a manually controlled switch 19 and with a plug 20 on the end of an external extension cord 21

for being plugged into a household electric outlet socket, or alternately it may comprise a conventional spring motor 22 that is hand wound by a key 23.

The dispensing mechanism comprises a rotatable disc 24 mounted on the upper end of motor shaft 25; the disc 24 having an elongated slot 26 therethrough which during rotation of the disc becomes aligned with a slot 27 through a stationary disc 28 secured on top of the case and with it aligned with a bottom opening 29 of the hopper mounted on the disc 28. The case has a stationary wall 20 located below the disc 24, the wall forming a downwardly inclined chute 31 at one end which protrudes outwardly of the case through a side opening 32. As shown in FIG. 3 it is to be noted that the space between the staionary disc 28 and wall 30 is approximately the same as a thickness of a cigarette, so that in use, when slot 26 comes into alignment with slot 27 and opening 29, one cigarette drops from the hopper into the slot 26, the cigarette then being carried by the rotating disc between disc 28 and wall 30 until it finally is brought over the chute 31 where the cigarette thus drops from slot 26, and rolls down the chute out of the case and comes to rest against an upward turned lip on stop 33, as shown.

In FIGS. 5 a design 34 of the invention is shown in which cigarettes are dispensed by a mechanism 35 that includes of drum 36 rotatable about a horizontal axis within a case 37, the drum having a longitudinal notch 38 on its cylindrical face, the notch coming into alignment with an opening 39 at the bottom of the hopper 40 so to carry a cigarette to the chute 41. This design of the invention is shown in FIGS. 5 through 7 operated by a dry cell battery 42 in an electric circuit with a motor 43 and switch 44. A slidale door 45 on the bottom of the case allows access to replace a worn out battery. As shown in FIG. 8 a mechanical, key wound timer 22 can be used in this design, instead of the electric power so to drive gear train 46 for rotating the drum.

Thus different forms of the invention have been provided.

While various changes may be made in the detail construction, it is understood that such changes will be within the spirit and scope of the present invention as is defined by the appended claims.

What I claim as new and desire to secure by Letters Patent is:

1. In a cigarette control dispenser, the combination of a hopper for containing a supply of cigarettes, a case upon which said hopper is mounted, said case containing a timer motor and a mechanism driven by said motor, said mechanism intermittantly in equally spaced time intervals dispensing said cigarettes one at a time, said hopper including at least one access opening near an upper portion thereof for re-loading cigarettes thereinto and an opening at its bottom from which said cigarettes are dropped into said mechanism, said timer motor having an output shaft that drives said mechanism, said timer motor being driven by conventional electrical or mechanical power, said mechanism comprising a rotating member mounted on said output shaft, said member having a recess that is equivalent to a length, width and thickness of one of said cigarettes, said recess aligning with said hopper bottom opening at each rotationg of said rotating member whereby only one of said cigarettes fits therein when gravity fed from said hopper, and an inclined chute extending outwardly

from said case, an inner end of said chute being in proximity with said rotating member so that when said recess is nearest said chute, said cigarette is gravity fed from said recess, upon said chute and rolled outward of said case, wherein said rotating member comprises a circular disc that rotates about a vertical axis between an upper and lower horizontal stationary plate of said

case, a space between said plates being equivalent to a clearance for said thickness of said cigarette, and one end portion of a lower of said plates over which said recess travels being angularly downward inclined to form an interior portion of said chute.
